G. E. ELIA.
SUBMARINE MINE.
APPLICATION FILED, APR. 17, 1917.

1,237,492.

Patented Aug. 21, 1917.

UNITED STATES PATENT OFFICE.

GIOVANNI EMANUELE ELIA, OF WESTMINSTER, LONDON, ENGLAND, ASSIGNOR TO
VICKERS LIMITED, OF WESTMINSTER, ENGLAND.

SUBMARINE MINE.

1,237,492.

Specification of Letters Patent. Patented Aug. 21, 1917.

Application filed April 17, 1917. Serial No. 162,801.

To all whom it may concern:

Be it known that I, GIOVANNI EMANUELE ELIA, a subject of the King of Italy, residing at Vickers House, Broadway, Westminster, 5 in the county of London, England, have invented certain new and useful Improvements in or Relating to Submarine Mines, of which the following is a specification.

This invention relates to submarine mines 10 of the kind comprising an anchor connected to the flotation chamber or mine proper by a mooring cable which is paid out from a drum located within the anchor, during the separation of the flotation chamber and 15 anchor after the mine has been launched, means being provided for controlling the paying-out of the cable so as to regulate the depth at which the flotation chamber will be anchored beneath the surface of the water. 20 In mines of this kind the controlling means usually comprise a plummet or sounding ball and a connecting line whose effective length is equal to the depth at which the flotation chamber is to be anchored beneath the 25 surface of the water.

According to the invention we dispense with the aforesaid plummet or sounding ball and provide a float connected by a line to suitable paying out gear in the anchor, the 30 length of the line between the float and the paying out gear being capable of adjustment, to determine the depth at which the flotation chamber will be eventually anchored beneath the surface of the water; the 35 paying out of the said line from its paying out gear commencing when the mine has sunk to a depth depending on the adjusted length of the portion of the float line between the float and the paying out gear. 40 The paying out of the said float line is effected by the pull of the float and causes translational movement to be imparted to a member serving as a stop for the paying out gear of the anchor cable, thus liberating the 45 anchor cable and permitting it to pay out as the flotation chamber rises and at the same time causing it to impart translational movement to another member forming part of the paying out gear of the anchor cable. 50 The translational movement of the stop member ceases when the float reaches the surface of the water, the anchor cable continuing to pay out until the other member above mentioned comes against the stop 55 member whereupon the paying out of the anchor cable ceases and the flotation chamber

ber remains anchored at the required depth beneath the surface of the water. The said members may be constituted by the drum on which the anchor cable is wound, and a 60 drum on which the float line is wound, said drum forming part of the paying out gear for the float line.

In order that the said invention may be clearly understood and readily carried into 65 effect the same will now be described more fully with reference to the accompanying drawing, in which:—

Figures 1, 2, 3, and 4 are diagrammatic views of one constructional form of the improved mine showing it in various positions which it assumes after being launched and finally anchored, and

Figs. 5 and 6 are diagrammatic views of two modified forms of the mine.

Referring to Figs. 1, 2 and 3; 1 is the flotation chamber, 2 is the float, and 3 is the anchor. 4 is the float line which is wound around the drum 5, and 6 is the anchor or mooring cable which is wound around the 80 drum 7. The drums 5 and 7 are rotatably mounted upon a fixed screw threaded shaft 8. Prior to the launching of the mine the float is separated from the drum 5 (as shown in Fig. 2) by a length h of the float line 4, 85 which corresponds to the depth at which the flotation chamber is to be anchored beneath the surface of the water, the drums 5 and 7 at this time lying in contact with each other as shown in Fig. 1. The drum 5 is free to 90 rotate and the drum 7 is locked against rotation so that as the anchor 3 descends, the paying out of the float line 4 by the pull due to the buoyancy of the float 2 will cause the drum 5 to revolve and at the same time move 95 axially along the shaft 8 into the position shown in Fig. 3. When the anchor reaches the sea bed, a pivoted locking lever 10 is moved about its fulcrum 11 and its extremity 12 disengaged from the toothed wheel 13 100 which constitutes one of the end walls of the drum 7, while its other extremity 14 is simultaneously brought into engagement with the toothed wheel 15 which forms one of the end walls of the drum 5, thereby locking the latter against further rotation. The anchor cable drum 7 being now released the flotation chamber 2 will ascend by its buoyancy, rotating the drum 7 as the anchor cable unwinds and causing it to travel axially along the shaft 8 until it comes into contact with the drum 5 which thus serves as a stop to 105 110

arrest further movement of the drum 7. Any suitable or well known device such as a hydraulic brake may be provided for retarding the paying out movement of the 5 drum 7. Assuming the distance x (Fig. 3) to represent the depth of the sea, the distance $x-h$ (Fig. 4) will represent the final position at which the flotation chamber comes to rest, h being the length of the portion 10 of the float line measured from the center of the flotation chamber and the float 2.

In the modified arrangement shown at Fig. 5, the drums 5 and 7 instead of being mounted on a single shaft common to both 15 are carried upon independent screw threaded shafts 16 and 17 respectively. The pitch of the screw threads on one of the said shafts may be different from that of the other shaft in which event the float line 20 drum 5 can be made of smaller diameter than the anchor cable drum 7 as shown. The operation of this arrangement is substantially the same as that described above with the exception that separate locking and 25 releasing devices 18 and 19 are shown for controlling the float line drum 5 and the anchor cable drum 7 respectively.

Instead of the abutment of one drum 30 against the other serving to limit the paying out movement of the anchor cable, other arrangements may be employed for this purpose. For example and as shown at Fig. 6, the float line drum 5 may be rigidly connected to a rotatably mounted screw threaded 35 shaft 20 which carries a nut 21 prevented from rotating by engaging with a rod 22 and capable of axial movement thereon. The anchor cable drum 7 is also rigidly connected to a rotatably mounted screw threaded 40 shaft 23 which carries a nut 24 also engaging with a rod 25 so as to be capable of axial movement only. Any convenient construction of locking and releasing devices, such for example as shown in Fig. 5, may be 45 provided for locking and releasing the float line drum and the anchor cable drum. The nuts 21 and 24 are so situated in relation to one another that the nut 24 appertaining to the anchor cable drum will, at the predetermined 50 time, abut against the other nut 21 to limit the paying out of the anchor cable. In a somewhat modified arrangement the nut 24 and rod 25 may be dispensed with and the anchor cable drum 7 may be rotatably 55 mounted on a fixed screw threaded shaft so that the drum 7 will itself abut against the nut 21 appertaining to the float line drum, to limit the paying out of the anchor cable.

It is to be understood that the invention is 60 not limited to any of the hereinbefore described constructions for carrying out the invention as any other construction will be suitable so long as it embodies the employment of two displaceable members one controlled by the paying out movement of the

anchor cable and the other by the paying out movement of the float line, the said members lying initially in contact with one another and becoming separated after the mine has sunk to a depth depending on the adjusted length of the float line and eventually coming together again when the flotation chamber rises from the anchor and assumes the proper distance beneath the surface of the water determined by the aforesaid adjusted length of the float line.

What I claim and desire to secure by Letters Patent of the United States:—

1. A submarine mine comprising the combination of an anchor adapted to sink when released in the sea, a buoyant chamber connected thereto and held in fixed relation to the anchor while the latter sinks, means for releasing the chamber from the anchor automatically when the anchor comes to rest to allow the chamber to rise, and means for automatically arresting the upward movement of the chamber when it has reached a predetermined distance below the surface of the sea comprising a member mounted on the anchor and a float connected to said member and adapted to position the member upon the anchor as the anchor sinks.

2. A submarine mine comprising an anchor, a flotation chamber, paying-out gear for said flotation chamber, a mooring cable connecting said flotation chamber to said paying-out gear, a float, paying-out gear for said float, a line connecting said float to said float paying-out gear, said float being separated prior to launching of the mine from said float paying-out gear by a length of line corresponding approximately to the depth at which the flotation chamber is to be anchored beneath the surface of the water, a member serving as a stop, said member being displaced during the sinking of the anchor by the paying out of the float line, another member which is displaced by the paying out of said mooring cable, said last mentioned member eventually abutting against said first mentioned member, and preventing further paying-out of the mooring cable when the flotation chamber has separated from the anchor and has reached a predetermined depth beneath the surface of the water.

3. A submarine mine comprising an anchor, a flotation chamber, paying-out gear for said flotation chamber, a mooring cable connecting said flotation chamber to said paying-out gear, a float, paying-out gear for said float, a line connecting said float to said float paying-out gear, said float being separated prior to launching of the mine from said float paying-out gear by a length of line corresponding approximately to the depth at which the flotation chamber is to be anchored beneath the surface of the water, a member serving as a stop, said member

being displaced during the sinking of the anchor by the paying-out of the float line, means for locking said member against further displacement when the anchor reaches 5 the sea bed, another member which is displaced by the paying out of said mooring cable, means for releasing said mooring cable paying-out gear when the anchor reaches the sea bed, and means for causing 10 said last mentioned member eventually to abut against said first mentioned member so to prevent further paying out of the mooring cable when the flotation chamber has separated from the anchor and has reached 15 a predetermined depth beneath the surface of the water.

4. A submarine mine comprising an anchor, a flotation chamber, a mooring cable, a member which is displaced by the paying 20 out of said mooring cable during the separation of the flotation chamber from the anchor, a float, a float line, a member which is displaced by the paying out of said float line during the separation of the float from 25 the anchor, the said members lying initially in contact with one another and becoming separated after the mine has sunk to a depth depending on the adjusted length of the float line which initially separates the float 30 from the anchor and eventually coming together again when the flotation chamber rises from the anchor and assumes a distance beneath the surface of the water determined by the aforesaid adjusted length of the float 35 line.

5. A submarine mine comprising an anchor, a flotation chamber, a mooring cable, a winch drum carrying said mooring cable which is displaced by the paying out of said 40 mooring cable during the separation of the flotation chamber from the anchor, a float, a float line, a winch drum carrying said float line which is displaced by the paying out of said float line during the separation of 45 the float from the anchor, the said winch drums lying initially in contact with one another and becoming separated after the mine has been sunk to a depth depending on the adjusting length of the float line which 50 initially separates the float line from the float line winch drum and eventually coming together again when the flotation chamber rises from the anchor and assumes a distance beneath the surface of the water determined by the aforesaid adjusted length 55 of the float line.

6. A submarine mine comprising an anchor, a flotation chamber, a mooring cable, a non-rotatable screw threaded shaft in said 60 anchor, an internally screw threaded and axially displaceable winch drum carrying said mooring cable and rotatably mounted upon said screw threaded shaft, a float, a

float line, an internally screw threaded and axially displaceable winch drum carrying 65 said float line which is also rotatably mounted upon said screw threaded shaft, the said winch drums lying initially in contact with one another and becoming separated after the line has sunk to a depth depending 70 on the adjusted length of the float line which initially separates the float line from the float line winch drum and eventually coming together again when the flotation chamber rises from the anchor and assumes a distance beneath the surface of the water determined by the aforesaid adjusted length 75 of the float line.

7. A submarine mine comprising an anchor, a flotation chamber, a mooring cable, 80 a non-rotatable screw threaded shaft in said anchor, an internally screw threaded and axially displaceable winch drum carrying said mooring cable and rotatably mounted upon said screw threaded shaft, means for 85 preventing rotation of said winch drum until the anchor approaches or reaches the sea bed, a float, a float line, an internally screw threaded and axially displaceable winch drum carrying said float line, means for 90 locking said float line drum against rotation when the anchor approaches or reaches the sea bed, said winch drums lying initially in contact with one another and becoming separated after the mine has sunk to a depth depending on the adjusted length 95 of the float line which initially separates the float from the float line winch drum and eventually coming together when the flotation chamber is released and rises from the anchor to a 100 distance beneath the surface of the water determined by the aforesaid adjusted length of the float line.

8. A submarine mine comprising the combination of an anchor, a buoyant chamber, 105 paying-out gear mounted on the anchor and connected to the buoyant chamber, means for automatically arresting the said paying-out gear controlled by the depth to which the mine sinks, and means for automatically 110 locking said arresting means.

9. A submarine mine comprising the combination of an anchor, a buoyant chamber connected thereto and held in fixed relation to the anchor while the latter sinks, means for releasing said chamber automatically 115 when the anchor comes to rest to allow the chamber to rise, and means for automatically arresting the upward movement of the chamber comprising a member mounted on 120 the anchor and a float connected to the member for operating the member as the anchor sinks an amount commensurate with the depth to which the anchor sinks.

GIOVANNI EMANUELE ELIA.
